(57) **CLAIM**

The ornamental design for a mobile phone, as shown and described.

DESCRIPTION

FIG. 1 is a first front view of a first embodiment of a mobile phone, showing our new design;

FIG. 2 is a first front perspective view thereof, showing the mobile phone in unfolded state;

FIG. 3 is a first back view thereof;

FIG. 4 is a first left side view thereof;

FIG. 5 is a first right side view thereof;

FIG. 6 is a first top view thereof;

FIG. 7 is a first bottom view thereof;

FIG. 8 is a second front view thereof, showing the mobile phone in the folded state;

FIG. 9 is a second front perspective view thereof;

FIG. 10 is a second back view thereof;

FIG. 11 is a second left side view thereof;

FIG. 12 is a second right side view thereof;

FIG. 13 is a second top view thereof;

FIG. 14 is a second bottom view thereof;

FIG. 15 is a first front view of a second embodiment of a mobile phone, showing our new design in the unfolded state;

FIG. 16 is a first front perspective view thereof;

FIG. 17 is a first back view thereof;

FIG. 18 is a first left side view thereof;

FIG. 19 is a first right side view thereof;

FIG. 20 is a first top view thereof;

FIG. 21 is a first bottom view thereof;

FIG. 22 is a second front view thereof, showing the mobile phone in the folded state;

FIG. 23 is a second front perspective view thereof;

(Continued)

FIG. 24 is a second back view thereof;
 FIG. 25 is a second left side view thereof;
 FIG. 26 is a second right side view thereof;
 FIG. 27 is a second top view thereof; and,
 FIG. 28 is a second bottom view thereof.
 FIG. 29 is a first front view of a third embodiment of a mobile phone, showing our new design in the unfolded state;
 FIG. 30 is a first front perspective view thereof;
 FIG. 31 is a first back view thereof;
 FIG. 32 is a first left side view thereof;
 FIG. 33 is a first right view thereof;
 FIG. 34 is a first top view thereof;
 FIG. 35 is a first bottom view thereof;
 FIG. 36 is a second front view thereof in the folded state;
 FIG. 37 is a second front perspective view thereof;
 FIG. 38 is a second back view thereof;
 FIG. 39 is a second left side view thereof;
 FIG. 40 is a second right view thereof;
 FIG. 41 is a second top view thereof;
 FIG. 42 is a second bottom view thereof;
 The broken lines in the figures show portions of the mobile phone that form no part of the embodiment in which they are shown.
